United States Patent Office.

GEORGE A. HUNTLEY, OF QUINCY, ILLINOIS.

Letters Patent No. 92,829, dated July 20, 1869.

COAL-STOVE.

The Schedule referred to in these Letters Patent and making part of the same.

To all whom it may concern:

Be it known that I, GEORGE A. HUNTLEY, of Quincy, in the county of Adams, and State of Illinois, have invented a new and improved Heating-Stove; and I do hereby declare that the following is a full, clear, and exact description of the construction and operation of the same, reference being had to the accompanying drawings, making a part of this specification, in which—

Figure 1 is a side view, a portion of the outer wall of the stove having been broken away.

Figure 2 is a horizontal section through line $z z$ of fig. 1.

This invention relates to that class of stoves in which a current of air, to be heated, is caused to pass up between the outer wall of the fire-pot and the inner wall of the stove-drum; and

The invention consists in the peculiar formation of said air-passage, whereby the current of air is made to pass either back and forth in a zigzag course, as it rises, or else to pass around the fire-pot in an ascending spiral line, so as to become thoroughly heated before it is discharged from the stove, the outer wall of the stove remaining comparatively cool all the while.

In the drawings—

A is that part of the drum or outer wall of the stove which encloses the fire-chamber;

B is an annular plate, attached to the top of the drum A;

C is a drum, resting upon the plate B, and fastened in place by rods and nuts, or screw-bolts;

D is the top of the stove;

E is the grate;

F is the ash-pit; and

G is the fire-pot, a space being left between the walls of the fire-chamber G and drum A, as shown in fig. 1.

This space is divided, by annular horizontal partitions $h h$, into several compartments, $H H' H''$, one over another.

Each compartment is also provided with a vertical partition, I, which prevents a current of air from passing continuously around the fire-pot.

The lower compartment, H, communicates with the next, H' , above it, through a small opening, a, in the partition h , alongside of the vertical wall I, so that the air, entering the compartment H, is obliged to pass around and escape through the opening a, into chamber H' . There it is obliged to turn to the right and pass entirely around the fire-pot, till it arrives at the opposite side of the wall I, when it finds another

opening, a', through which it can escape into the next compartment, H'' , above, and so on, as many compartments being employed as may be thought best.

From the upper compartment H'' , it escapes through the hole J, or through a pipe inserted into the hole, and passes to the apartment that is to be warmed.

It will be observed that the air is thus forced to travel slowly around the fire-pot, so as to become thoroughly heated. This is effected much better by the arrangement described, than by means of a spiral pipe, since, in the latter, the current passes continuously and rapidly around the stove, and escapes but partially heated, while, by my apparatus, the air travels slowly around the fire-chamber, escaping in a rapid jet through the holes a a', from one apartment to the other.

When moving slowly in the several apartments, it has an opportunity to circulate up and down and laterally during its passage, so as to become thoroughly intermingled and uniformly heated; whereas, if impelled almost directly forward at a considerable velocity, it would not become thus thoroughly intermingled before it escapes through the hole J, or through a pipe inserted into the hole, and passes to the apartment that is to be warmed.

It is evident that if the walls I I were in the same vertical line, the current could be made to pass in a zigzag course around the stove, the effect of which would be the same as the arrangement above described.

Having thus described my invention, I do not claim the application of a spiral tube between the walls G and A, to convey a current of air; but

What I do claim as new, and desire to secure by Letters Patent, is—

The arrangement, in a stove, of the horizontal partitions $h h$ and vertical partitions I I, in connection with the walls A G and small passages a a', as described, whereby the air is made to circulate slowly around the fire-pot in the large horizontal passages $H H' H''$, escaping rapidly from one passage to another through the small holes a a', substantially as, and for the purposes specified.

In testimony that I claim the above, I have hereunto subscribed my name, in the presence of two witnesses.

GEORGE A. HUNTLEY.
